United States Patent Office

Des. 194,286
Patented Dec. 25, 1962

194,286

BOTTLE

Henry Lilling, Brooklyn, N.Y., assignor, by mesne assignments, to Ultra-Chemical Works, Inc., Paterson, N.J.

Filed Apr. 6, 1962, Ser. No. 69,615

Term of patent 14 years

(Cl. D58—6)

FIG. 1 is a top plan view of a bottle, showing my new design;

FIG. 2 is a side elevational view thereof; and

FIG. 3 is an end elevational view thereof.

The side and end not shown are substantially like the side and end shown.

I claim:

The design for a bottle, as shown and described.
